UNITED STATES PATENT OFFICE

104,058

DESIGN FOR A TOBACCO PIPE

Michael Mason Warner, Chicago, Ill.

Application April 11, 1936, Serial No. 62,072

Term of patent 14 years

To all whom it may concern:

Be it known that I, Michael Mason Warner, a citizen of the United States, residing at Chicago, in the county of Cook and State of Illinois, have invented a new, original, and ornamental Design for a Tobacco Pipe, of which the following is a specification, reference being had to the accompanying drawing forming a part thereof.

I claim:

The ornamental design for a tobacco pipe substantially as shown.

MICHAEL MASON WARNER.
